UNITED STATES PATENT OFFICE.

HEINRICH SCHIEFERSTEIN, OF CHARLOTTENBURG, NEAR BERLIN, GERMANY, AS-
SIGNOR TO WESTINGHOUSE ELECTRIC & MANUFACTURING COMPANY, A COR-
PORATION OF PENNSYLVANIA.

RADIO TRANSMISSION SYSTEM.

Application filed October 31, 1921, Serial No. 511,774, and in Germany January 26, 1921.

My invention relates to radio transmission devices and particularly to combinations including a vacuum-tube generator and a radiation circuit connected by a link circuit.

It is an object of my invention to provide a system of connections whereby the closeness of coupling may be varied without corresponding change in the tuning, and the tuning may be varied without causing corresponding changes in the coupling.

Other objects of my invention will be apparent from the following detailed description and the accompanying drawing, in which the single figure is a diagrammatic illustration of apparatus and circuits embodying my invention.

In the figure, the vacuum tube 1 is provided with the usual cathode 2, anode 3 and control electrode 4. The anode and cathode are connected by a plate-circuit including an inductor 5, at least a portion of which is in inductive relation to an inductor 6 connected between the control electrode 4 and the cathode 2. The plate-circuit also includes a source of energy 7.

The oscillation generator is united with a radiation circuit 11 by means of a link circuit 12. The link circuit includes an inductor 13 which is inductively related to at least a portion of the inductor 5. This relation is adjustable. The adjustment may include means for varying the inductance of the inductor 5, the inductance of the inductor 13, the mutual inductance between them or all three inductances.

The link circuit also includes an inductor 14 inductively related to the inductor 6, and an inductor 15 inductively related to an inductor 16 in the radiation circuit. A provision for adjustment of the inductors 15 and 16 is made, which may include means for adjusting either the inductance of one inductor, the inductance of the other inductor, the mutual inductance between them or all three.

In the operation of the device, the plate-circuit 3, 5, 7, 2 delivers energy to the grid-circuit by the inductive relation between inductors 5 and 6, and also by way of the link circuit. The link circuit receives energy from the plate-circuit by the inductive

coupling 5—13, and delivers energy to the grid-circuit by the inductive coupling 6—14.

The link circuit also delivers energy to the radiating circuit by the inductive coupling 15—16. The adjustment of the coupling between inductors 5 and 13 and inductors 15 and 16 will control the coupling between the radiating circuit and the generator. This coupling may, if desired, be changed without changing the inductance in the inductor 5, or in the inductor 16. It is therefore possible to change the coupling without changing the tuning of either circuit.

By proper adjustments of the variable inductances, the ratio between the voltage across the inductor 13 and the voltage across the inductor 15 may be changed without changing the coupling. It is therefore possible not only to control the tuning without changing the coupling, but to control the distribution of energy between the generator and the radiating circuit without altering the tuning. By this means it is possible to so adjust the device that the maximum efficiency is obtained.

It will be observed that the link circuit contains no capacity except the distributed capacity of the several windings. This distributed capacity is so small that, for all practical purposes, the link circuit may be regarded as an aperiodic circuit.

Although I have illustrated and specifically described only a single form of my invention, it will be obvious to those skilled in the art that many variations thereof are possible. I, therefore, do not wish to be limited, except as required by the prior art or indicated in the following claim.

I claim:

In a radio sending device, an oscillation generator, including a feed-back coupling, a radiating circuit, a link circuit, transformers coupling said link circuit to said oscillation generator and said radiating circuit respectively, one of said transformers including members which are also a part of said feed-back coupling.

In testimony whereof I affix my signature.

HEINRICH SCHIEFERSTEIN.
